TAPE-APPLYING MACHINE

Walter P. Osgood, Malden, Mass.

Application January 21, 1935, Serial No. 2,634

20 Claims.

(Cl. 12—51)

The present invention relates to machines for applying strip material to shoe upper parts, and more particularly to top taping machines of the type in which the free end of an adhesively-coated tape in a roll is progressively pressed downwardly upon a work piece interposed between a support and a cooperating pressing and feeding member for effecting the adhesion of the tape and the work and a feed movement thereof until the required length of tape has been applied to the work piece. It should be understood, however, that some of the features of the present invention may be used to advantage in back-seam taping machines, in machines for applying strip material other than tape to shoe upper parts, and in tape-applying machines of another type wherein the strip material is interposed between the support and the shoe upper part, the latter being interposed between the strip material and the pressing member.

In some top taping operations it is desirable that the strip material, such as tape, be applied to the work piece with one edge of the tape flush with the edge of the work piece. In others, the edge of the tape is located entirely within the edge of the work piece, there being a space between the adjacent edges of the tape and the work piece. In still others, the strip material, such as piping, is applied to the work piece with one edge of the piping projecting beyond the edge of the work piece. It is highly desirable that the spacing, or lack of spacing, between the adjacent edges of the work piece and the strip material be uniform throughout the extent of the work piece.

Heretofore considerable difficulty has been encountered in the operation of the type of top taping machine hereinbefore referred to when tape is applied to a work piece along an edge which has a pronounced lateral curvature such, for instance, as the convexly and concavely curved edges along the wing and throat, respectively, of a vamp. When tape is applied along an edge which has a pronounced lateral curvature the operative is required to swing the work piece against the work guide in order to maintain the curved edge of the work piece in the line of feed.

Heretofore the tape has been directed upon the work piece by a tape guide having a slot through which the tape travels. When a straight portion of the edge of the work to be taped is transferred along the work guide, the direction of travel of the work and the direc-

tion of pull exerted by the applied tape upon the tape in the slot of the tape guide coincide, i. e., are on the same straight line, with the result that so long as the edge portion of the work engaged with the work guide is a straight edge portion, the tape is applied to the work in the desired position. When, however, a curved edge portion of the work is engaged by the work guide, necessitating that the work be swung against the work guide, the desired position of the tape on the work can no longer be maintained for the curved edge. The reason for this is that although the tape tends to issue from the slot in the tape guide in a straight line, the point of pull of the tape last applied to the work is moving laterally with respect to the tape issuing from the slot since the curved edge of the work is being swung against the work guide and the point of pull of the applied tape is no longer moving in a straight line. Stated in another way, although for a straight edge portion of the work the work guide establishes a predetermined relationship between one edge of the tape and the adjacent edge of the work, for a curved edge portion of the work the work guide can establish only an approximate of this predetermined relationship. The result of this situation is that if the vertical sides of the slot confine the tape laterally, the direction of pull between the tape in the guide and the point where the tape has been last applied to the work piece is on a chord intersecting the curved edge, the chord extending outside a concavely curved edge and inside a convexly curved one. With such a tape guide the tape cannot be applied properly to an edge having a pronounced lateral curvature as the edge of the tape adjacent the point of application is constrained to follow the chord hereinbefore referred to.

Heretofore attempts have been made to remedy this difficulty by elongating the slot in the tape guide laterally so as to leave the tape free to shift bodily in the tape guide under the pull on the tape directed along the chord hereinbefore referred to. Experience has demonstrated that this change in construction did not remedy the difficulty, the only change noted being an error in the position of the tape reverse of that which occurred when the slot in the tape guide confined the edges of the tape laterally.

The principal object of the present invention is to produce a tape-applying machine of the type first referred to by which the tape may be applied uniformly throughout its extent to the

edge of a work piece having a pronounced lateral curvature.

To the accomplishment of this object a feature of the invention contemplates the provision in a tape-applying machine having a support over which a piece of sheet material having a curved edge is fed and swung, means for pressing the tape against the material and a guide for engaging the edge of the material and against which the material is swung during the application of the tape to the work, of means for directing the tape upon the material with one edge of the tape in a position of predetermined relationship with respect to the adjacent curved edge of the material during the swinging of the material against the guide and the transfer of the tape along the curved edge of the material.

The predetermined relationship may require one edge of the tape to be flush with the adjacent edge of the work, or to extend in a spaced relationship therewith.

In the broader aspects of the invention the predetermined relationship between one edge of the tape and the adjacent curved edge of the work may be effected by mechanism which shifts relatively the tape and the work in accordance with the extent and direction of curvature of the edge of the work at the point of tape application.

Because of its simplicity, it is preferred that the predetermined relationship between one edge of the tape and the adjacent edge of the curved work throughout the transfer of the point of application of the tape therealong be effective by providing the tape-applying machine of the type first referred to with a tape-guide constructed and arranged to allow the tape to swing bodily therein laterally under the influence of the moving work.

In the illustrated embodiment of the invention the tape-guide is provided with a surface generated by a moving straight line which continuously intersects a circumference of a fixed circle and is constantly parallel to a given fixed straight line, but it should be understood that the directrix of the cylindrical surface may be any curve.

A further object of the present invention is to produce a tape-applying machine having its various parts constructed and arranged to operate in an improved manner so that the pressing and feeding member which cooperates with the work support and effects the adhesion of the tape and the work and a feed movement thereof can be run at a high rate of speed without objectionable vibration and without excessive wear on the parts and so that the machine can produce as good, and in some respects, better work than machines of the prior art.

To the accomplishment of this further object, and such others as may appear hereinafter, the various features consist in certain devices, combinations and arrangement of parts, hereinafter described and then set forth broadly and in detail in the appended claims which possess advantages readily apparent to those skilled in the art.

The various features of the present invention will be understood readily from an inspection of the accompanying drawings illustrating the best form of the invention at present known to the inventor, in which,

Fig. 12 is a diagrammatic view in plan illustrating the application of tape to the throat of a vamp, and

Fig. 13 is a diagrammatic view illustrating somewhat exaggerated the manner in which the tape swings in the tape guiding throat during the application of the tape to a concave edge portion of the work.

The illustrated embodiment of the present invention applies tape to a shoe upper part provided with pronounced lateral curvatures, said shoe upper being illustrated herein for convenience of disclosure as a vamp 14 (Figs. 10 and 12) provided with convexly curved wing portions 15 and a concavely curved throat portion 16. The machine is provided with a work support in the form of a roll 17 over which the work is fed and a presser member 18 which has a movement toward and from the work support and which by such movement applies the tape to the work. The presser member also has a movement while it is engaged with the work in order to feed the taped work rearwardly. During the feed of the work its edge is engaged by a guide 19 against which the work is swung by the operative to maintain the curved edges of the work in the line of feed. The tape is directed upon the work by a tape-guiding throat 20 constructed to direct the tape upon the work in a position of predetermined relationship between one edge of the tape and the adjacent edge of the work throughout the transfer of the point of application of the tape therealong. As usual, the machine is provided with a tape-severing knife 21 and a pull-off device for pulling tape from a source of supply 23.

The work supporting roll 17 is rotatably mounted upon one end of a stub-shaft 24 (Fig. 7) which is carried by a yoked arm 25 secured to a horizontal rock-shaft 26 journaled in a hollow frame 27. The roll 17 is spaced forwardly from the frame 27 and laterally from the arm 25 to provide clearance for supporting and permitting the swinging movement of a large piece of work such, for instance, as a made upper closed by a back seam. The work guide 19 is supported adjustably from the arm 25 in a well known manner.

The arm 25 (Figs. 7 and 9) is provided with an extension 28 the free end of which carries a

5 pivot pin 29 pivotally connected to one end of a double-yoked link 30, the other end of which is pivotally mounted on a pivot pin 31 carried by the yoked arm of a bell-crank lever 32 which is pivotally mounted on a horizontal rod 33 secured to the frame 27. The pin 31 supports loosely a block 34 into which is threaded one end of a rod 35 the other end of which extends loosely through a strip 36 and the frame 27. The 10 work support 17 is pressed yieldingly toward the pressing member 18, through the connections described, by a spring 37 which is coiled about the rod 35 and interposed between the block 34 and the strip 36, there being suitable thumb-nuts 15 38 and 39 to adjust the position of the rod 35 and to lock it in adjusted position. The strip depends somewhat loosely from the shank of a bolt 40 threaded into the frame 27. The tension of the spring 37 may be adjusted by a thumb-screw 41 having its shank threaded into the frame 27 and its point engaged with the lower end of the strip 36. The work support 17 may be lowered against the tension of the spring 37 by a treadle-rod 42 pivotally connected to the other 20 arm of the bell-crank lever 32.

25 The pressing member 18 is mounted upon one end of a rock-shaft 43 (Figs. 1 and 9) which is rotatably mounted in one long and one short arm of a yoked-carrier 44 (Fig. 6) secured to a rock-shaft 45 one end of which is journaled in the frame 27 and the other of which is journaled in a head 46 (Fig. 4) extending forwardly therefrom. Keyed to the rock-shaft 43 (Fig. 9) is a strap 47 formed on one end of a link 48. The other end of the link 48 consists of a strap 49 engaged with an eccentric 50 on a horizontal shaft 51 journaled in bearings 52 (Fig. 4) carried by the frame 27. The shaft 51, outside the frame 27, is provided with a pulley 53 (Figs. 4 and 6) which is driven in the direction of the arrow, Fig. 9, from some suitable source of power through a belt 54. The eccentric 50 is extended rearwardly (Fig. 4) to form a support upon which a counterbalance 55 is secured.

45 With this construction the vertical throw of the eccentric 50 causes the link 48 to oscillate the carrier 44 and the rock-shaft 45, thus imparting movement to the presser member 18 toward and from the work support 17. The 50 lateral throw of the eccentric 50 causes the link 48 through its key connection with the rock-shaft 43 to oscillate it in the carrier 44, thus imparting the feed movement to the presser member 18. Stated in another way, oscillation 55 of the carrier 44 and the rock-shaft 45 carried thereby imparts a compound movement to the pressing member 18.

60 The mechanism for imparting the compound movement to the pressing member 18 is exceedingly strong and rigid, and can be run at a high rate of speed without objectionable vibration and without excessive wear on the parts. While it is preferred to connect the carrier 44 and the rock-shaft 45 as shown, the desirable compound 65 movement may be imparted to the pressing member 18 by the combined rocking movement of the rock-shaft 43 in the carrier 44 and of the carrier 44 on a shaft corresponding to the shaft 45 but held rigidly in the frame 27.

70 For the purpose explained in my Patent No. 1,549,376, August 11, 1925, the presser member 18 is slotted to receive the lower ends of two pivot fingers 56 and 57 (Figs. 2 and 3) the upper end of each of which is pivotally mounted on a 75 block 58. The upper end of the block 58 is sup-

ported by a stud 59 (Fig. 3) bolted to a bracket 67 secured to the head 46. Each pivot finger 56 or 57 is pressed yieldingly against the work by a spring 60, (Figs. 1 and 2). It will be understood by those skilled in the art that along the 5 pronounced lateral curvatures on the wings 15 and the throat 16 of the vamp 14 (Fig. 12) the tape will be plaited slightly in accordance with the showing of Fig. 7 of my patent hereinbefore identified, which showing is, however, somewhat 10 exaggerated to facilitate disclosure.

The tape to be applied to the work is mounted in individual rolls upon a horizontal spindle 61 (Fig. 1) projecting laterally from the upper end 15 of a bracket 62 the lower end of which is secured to a cover 63 for the parts within the frame 27. The loose end of the tape is withdrawn from one of the rolls and led with its adhesive face uppermost over a piece of bent wire 64 secured to the bracket 67 and thence under an elongated 20 roll 65 (Fig. 2) rotatably mounted on a stud 66 projecting forwardly from the bracket 67. From the roll 65 the tape passes over an elongated roll 68 carried by one end of a lever 69 pivoted on the bracket 67. From the roll 70 the tape passes 25 over a roll 71 supported from the upper end of an arm 72 secured at its lower end to the block 58. From the roll 72 the tape passes first through a slot 73 formed in a bracket 74 adjustably secured to the front face of the block 58 and then 30 through a slot 75 formed in an arm 76 adjustably secured to the left hand face of the block 58.

35 The tape is directed upon the work by the throat 20 secured to the lower end of a lever 78 which is provided with a slot 79 intermediate its ends to receive loosely the reduced forward end of the rock-shaft 45. As shown particularly in Figs. 11 and 13, the tape in passing through the throat 20 is supported by a closed cylindrical surface, the diameter of which is less than the 40 width of the tape. Thus the tape is bent laterally about a fixed axis extending longitudinally of the tape.

45 With this construction, the edge guide 19 is adjusted in accordance with the proper or predetermined relationship that should exist between the edge 80 of the tape and the adjacent edge of the work, it being understood that by reason of the chording effect noted above the edge guide 19 itself provides with respect to the 50 curved edge of the work only an approximate of the tape edge and curved edge relationship desired. Once the approximate of the proper tape edge and work edge relationship is provided for by adjustment of the work guide 19, the tape 55 guide 20 functions automatically to bring the edge of the tape and the adjacent curved edge of the work into the proper or predetermined relationship during the swinging of the curved edge of the work against the guide 19. It will 60 be understood that the edge 80 of the tape may be flush with the adjacent edge of the work, be spaced from the adjacent edge, or project beyond the edge.

65 When the tape is being applied to the convexly curved wings of the vamp 14 the operative swings the untaped portion of the vamp to the left, viewing Fig. 10, against the guide 19 as a center in order to maintain the convexly curved edge in the line of feed. The direction of pull 70 between the tape fixed to the work and the loose tape in the throat is along a chord intersecting the convex curve. This pull swings the tape bodily laterally to the left, viewing Fig. 11, but the extent to which the tape is swung to the 75

left is controlled by the cylindrical surface which compels the edge 80 to turn upwardly into a vertical plane substantially tangentially to the curved edge of the work at the next succeeding point of tape application.

When the tape is being applied to the concavely curved throat of the vamp 14 the operative swings the untaped portion of the vamp to the right, viewing Fig. 12, about the guide 19 as a center in order to maintain the concavely curved edge in the line of feed. At the same time the tape is swung bodily to the right, viewing Fig. 13, thus maintaining the edge 80 of the tape in the proper operating position relatively to the curved edge of the work at the next succeeding point of tape application.

In the illustrated embodiment of the invention the roll 68 is employed as a pull-off to pull the tape from the source of supply, thus to insure the application of the tape to the work and the feed of the work under the same tension. To this end the lever 69 (Figs. 1 and 2) is pivoted to one end of a link 81, the lower end of which is connected pivotally to the carrier 44 within a slot 82 formed therein. Thus the oscillating carrier 44, through the link 81, imparts alternating up and down strokes to the pull-off roll 68 which acts to pull tape from the source of supply on the up stroke and to release the tape on the down stroke to permit the pressing member 18 to draw the tape through the throat 20 free of the source of supply tension.

During the operation of the pull-off roll 68 to pull tape from the source of supply, the roll 65 is rotated in a counterclock-wise direction, viewing Fig. 2. To prevent rotation of the roll 65 in a clock-wise direction, viewing Fig. 2, the stud 66 carries a ratchet 83 which is engaged by a pawl 84 secured to the bracket 67. When the pull-off roll 68 is moved to pull tape from the source of supply the lever 69 is elevated and a spring plate 85, connected by one end thereto, is depressed into engagement with the tape passing over the roll 71, thus preventing the tape roll 68 from pulling tape backwardly through the throat 20.

The tape-severing knife 21 is provided with a V-shaped cutting edge 86 (Fig. 5) which is secured to one end of a lever 87 pivoted on the reduced forward end of the rock-shaft 45. The tape-severing knife 21 is actuated in a direction to sever the tape by a coiled spring 88 (Fig. 2) one end of which is connected to the bracket 67 and the other end of which is connected to the upper end of the lever 87. The lever 87 is held normally in the position of Fig. 2 against the tension of the spring 88 by a latching means comprising a cam surface 89 formed on the front edge of the lever 78 and a block 90 (Figs. 2 and 5) secured to the lever 87.

In order to disengage the latching means at the will of the operative, the upper end of the lever 78 is pivotally connected to one end of a bell-crank lever 91 which is pivoted on the stud 59. The other end of the bell-crank lever 91 is provided with a finger-piece 92 arranged as close as may be to the work support 17 so that the operative in feeding the work through the machine may engage the finger-piece 92 in the same general direction as the feed of the work. When the operative engages the finger-piece 92 the lever 78 is elevated to bring the throat 20 out of the path of the tape-severing knife 21 and to locate a recess 93 formed in the lever 78 opposite the block 90. The latching means is

thus disengaged to allow the spring 88 to actuate the knife to sever the tape.

In order to limit positively the active tape-severing stroke of the knife 21 and to return the knife to its original position, the carrier 44 is provided with a plate 94 (Figs. 2 and 6) which engages the lever 87, above its pivotal connection, on the upward swing of the carrier 44 to lift the presser member 18 from the work.

During the tape-severing operation it is desirable to hold the tape extending rearwardly of the work taut. To this end the bell-crank lever 91 is provided with a third arm 95 (Fig. 3) from which is supported a lateral pin 96 arranged to press the plate 85 firmly into engagement with the tape passing over the roll 71.

When the operative releases the finger-piece 92 the parts are restored to the position of Fig. 2 by a coiled spring 97, one end of which is secured to a pin 98 (Fig. 3) projecting laterally from the third arm of the bell-crank lever 91, and the other end of which is connected to a pin 99 (Fig. 4) projecting laterally from the bracket 67. The movement of the lever 91 under the influence of the spring 97 is limited by an adjustable stop 100 (Figs. 1 and 2) secured to the bracket 67 and arranged to engage the pin 98.

With this construction the knife 21 will be operated continuously by the spring 88 on its active stroke and by the carrier 44 on its idle stroke as long as the operative maintains the finger-piece 92 depressed. As soon, however, as the finger-piece 92 is released, the spring 97 will return the throat 20 to the position of Fig. 2. During this return movement of the throat 20 the cam surface 89 wedges the block 90 to the right (Fig. 2) thus re-engaging the latching means which holds the knife out of operation.

Nothing herein explained is to be interpreted as limiting the various features of the present invention in the scope of its application to use in connection with the particular machine or the particular mode of operation or both selected for purposes of illustration and explanation. While the particulars of construction herein set forth are well suited to one mechanical form of the invention and to the use to which it is put, it is not limited to this use, nor to these details of construction, nor to the conjoint use of all its features, nor is it to be understood that these particulars are essential since they may be modified within the skill of the artisan without departing from the true scope of the actual invention, characterizing features of which are set forth in the following claims by the intentional use of generic terms and expressions inclusive of various modifications.

What is claimed as new, is:

1. In a tape-applying machine, the combination with a work support, means cooperating with said work support for applying tape to the work and for feeding the taped work, and means for guiding the work as it is swung on the work support to transfer the point of application of the tape along curved marginal portions thereof, of means for guiding the tape to the point of application constructed to permit the tape to swing bodily therein laterally under the influence of the moving work.

2. In a tape-applying machine, the combination with a work support and means cooperating therewith for applying tape to the work, of means for guiding the tape to the point of application.

- lication and for bending a portion of the tape about an axis extending longitudinally thereof.
3. In a tape-applying machine, the combination with a work support and a tape-applying device, of a tape-guiding throat having an opening through which the tape passes and in which the tape may swing, said opening being narrower than the tape.
4. In a tape-applying machine, the combination with a work support and a device cooperating with the work support for applying tape to the work and for feeding the taped work, of a tape-guiding throat having a curved surface upon which the tape may swing.
- 10 5. In a tape-applying machine, the combination with a work support and a device cooperating with the work support for applying tape to the work and for feeding the taped work, of a tape-guiding throat having substantially a cylindrical tape-supporting surface.
- 20 6. In a tape-applying machine, the combination with a work support and a tape-applying device, of a tape-guiding throat having substantially a closed cylindrical tape-supporting surface the diameter of which is less than the width of the tape.
- 25 7. A tape-applying machine having, in combination, a work support, a device cooperating with said work support for applying tape to the work, and means for imparting a compound movement to said device comprising a rock-shaft upon which the device is mounted, a carrier for the rock-shaft and mechanism for oscillating the rock-shaft and the carrier.
- 30 8. A tape-applying machine having, in combination, a work support, a device cooperating with said work support for applying tape to the work, and means for imparting a compound movement to said device comprising a rock-shaft upon which the device is mounted, a carrier for the rock-shaft, a rock-shaft upon which the carrier is mounted, and mechanism for oscillating the rock-shafts.
- 35 9. A tape-applying machine having, in combination, a work support, a device cooperating with said work support for applying tape to the work, and means for imparting a compound movement to said device comprising a rock-shaft upon which the device is mounted, a carrier for the rock-shaft, an eccentric, and connections between the eccentric and the rock-shafts for oscillating them.
- 40 10. A tape-applying machine having, in combination, a work support, a rock-shaft, a tape-applying device carried thereby, an eccentric, a link having an eccentric strap at one end and a strap keyed to the rock-shaft at the other end, a second rock-shaft journaled in the frame of the machine, and a carrier secured to the second rock-shaft supporting the first named rock-shaft.
- 45 11. A tape-applying machine having, in combination, a work support, a tape-applying device, and means for supporting the tape-applying device including a rock-shaft and an oscillating carrier therefor.
- 50 12. A tape-applying machine having, in combination, a work support, a tape-applying device,
- 55 and means for supporting the tape-applying device including a floating rock-shaft.
- 60 13. A tape-applying machine having, in combination, a support, means for pressing a tape and a work-piece together on said support and for causing a feed movement thereof over said support, means for severing the tape adjacent to the point of attachment to the work, means for imparting a tape-severing stroke to the tape-severing means, and separate means for operatively connecting said severing and work feeding means to return the severing means to its original position.
- 10 14. In a tape-applying machine, the combination with a tape-severing knife and a spring for imparting a cutting stroke to the knife, of a stop for limiting the cutting stroke of the knife.
- 15 15. In a tape-applying machine, the combination with a tape-severing knife and a spring for imparting a cutting stroke to the knife, of a power operated stop for limiting the cutting stroke of the knife.
- 20 16. A tape-applying machine having, in combination, a knife for severing the tape, said knife having an active and an idle stroke, yielding means for actuating the knife on its active stroke and positive means for actuating the knife on its idle stroke.
- 25 17. A tape-applying machine having, in combination, tape-applying mechanism, tape-severing mechanism, a spring for imparting a tape-severing stroke to the tape-severing mechanism, latching means for retaining the tape-severing mechanism out of operation, means under the control of the operative for disengaging the latching means, and automatic mechanism for throwing the tape-severing mechanism out of operation.
- 30 18. A tape-applying machine having, in combination, tape-applying mechanism, tape-severing mechanism, a spring for imparting a tape-severing stroke to the tape-severing mechanism, latching means for retaining the tape-severing mechanism out of operation, means under the control of the operative for disengaging the latching means, and automatic mechanism for throwing the tape-severing mechanism out of operation and for re-engaging the latching means.
- 35 19. In a tape-applying machine, the combination with a work support, means cooperating with said work support for applying tape to the work and for feeding the taped work, and means for guiding the work as it is swung on the work support to transfer the point of application of the tape along the curved marginal portions thereof, of means for guiding the tape to the point of application constructed to bend a portion of the tape about an axis extending longitudinally thereof and to permit the bent portion of the tape to swing bodily therein laterally under the influence of the moving work.
- 40 20. In a tape-applying machine, the combination with a work support and a tape-applying device, of a tape-guiding throat having a tape-supporting surface substantially like the inner surface of a ring.

WALTER P. OSGOOD.
